FLOWER TRELLIS OR SIMILAR ARTICLE

Walter Thompson, Colorado Springs, Colo.

Application May 27, 1948, Serial No. 146,633

Term of patent 14 years

(Cl. D35—3)

To all whom it may concern:

Be it known that I, Walter Thompson, a citizen of the United States, residing at 717 North Union Street, Colorado Springs, in the county of El Paso and State of Colorado, have invented a new, original, and ornamental Design for a Flower Trellis or Similar Article, of which the following is a specification, reference being had to the accompanying drawing, forming part thereof.

Fig. 1 is a front elevation of a flower trellis, showing my new design; and

Fig. 2 is a side elevation of the flower trellis shown in Fig. 1.

I claim:

The ornamental design for a flower trellis or similar article, as shown.

WALTER THOMPSON.
